UNITED STATES PATENT OFFICE.

WILLIAM EHRLICH, OF CHICAGO, ILLINOIS, ASSIGNOR TO CASE & MARTIN COMPANY, OF CHICAGO, ILLINOIS, A CORPORATION OF ILLINOIS.

PIE RIMMING AND PINCHING MACHINE.

Application filed January 3, 1922. Serial No. 526,621.

To all whom it may concern:

Be it known that I, WILLIAM EHRLICH, a citizen of the United States, residing at Chicago, in the county of Cook and State of Illinois, have invented certain new and useful Improvements in Pie Rimming and Pinching Machines, of which the following is a specification.

My invention relates to machines for forming the rim of pies and has for its object the provision of simple and efficient mechanism for automatically forming the rim and pinching the edge to serrate or roughen the latter.

Other objects will appear hereinafter.

An embodiment of my invention is illustrated in the accompanying drawings, forming a part of this specification, and in which—

Fig. 1 is a side elevation of one end of a machine embodying my invention;

Fig. 2 is an end elevation of the other end of said machine;

Fig. 3 is a cross-section through the central portion of Fig. 1; and

Fig. 4 is an enlarged fragmental plan view of a clutch used in the construction.

Referring more particularly to the drawings, I have indicated a frame consisting of uprights 5 at the ends with a member 6 connecting the tops of said uprights. The receiving end of the machine is indicated in Fig. 2 and mounted on the upright is a pulley 7 which cooperates with a similar pulley 8 at the other end of the machine for operating an endless conveyer 9. The pulleys 7 and 8 may be arranged in any manner to support a desirable endless conveyer. A conveyer suitable for this device consists

of a wide belt 10 secured to two sprocket chains 11. It is desirable to provide the sprocket chains in order to prevent the belt from slipping on the pulleys 7 and 8, for the belt must be timed with respect to pulley 8, particularly. Pulley 7 is preferably mounted on a block 12 which is slidably mounted in a guide 13 and provided with a screw 14 which passes through a yoke 15 on the guide 13. A nut 16 is threaded on the bolt 14 for adjusting the block 12 to tighten the conveyer when desirable.

On the conveyer is a plurality of members 18 each having an opening therein. In the opening is a rod 19 which extends through the conveyer and has a pie-tin holder 20 secured at its upper end. A spring 21 is mounted on the rod 19 so as to hold the pie-tin holder firmly against the block or mounting 18.

The pulley 8 is preferably made up of a primary wheel part 22 which has a hub 23 journaled on a sleeve 24 which is a part of the upright 5. On the front side of wheel 22 is an annular member 25 which has its outer periphery formed similarly to the wheel 22 for engaging the endless conveyer 9. The member 25 is held to wheel 22 by bolts and spacers 26. On the rear side of wheel 22 is mounted a ring 27 which has its rear side plane for a purpose to be more fully described hereinafter. The ring 27 is held against lugs 28 on wheel 22 by means of the bolts 26, as clearly indicated in Fig. 3. The hub 23 has a restricted portion upon which a driving gear 29 is fixed, and said gear meshes with a pinion 30 fixed on a shaft 31 which is mounted in the upright 5 and an auxiliary bearing 32. The shaft 31 has a disc clutch member 33 fixed thereon, and the member 33 is adapted to cooperate with a disc clutch member 34 fixed on a hub 35 which is journaled on shaft 31. The hub 35 carries a beveled gear 36 which meshes with a pinion 37 on a vertical shaft 38 which carries a beveled gear 39 meshing with a pinion 40 on a shaft 41 and the latter is driven through gears 42 by an electric motor 43 or other suitable driving means. It will be noted that shafts 38 and 41 are also mounted in suitable bearings on the device.

Suitable pressure is applied to the shaft 31 through a collar 44 fixed on said shaft by a spring 45 bearing against a suitable boss on frame 5. A ball bearing 46 or other friction alleviating means may be provided between the collar 44 and spring 45. Also, a ball bearing or other friction alleviating means may be provided between the hub 35 and bearing 32, as indicated at 47. The clutch members 33 and 34 are thus held together at all times and when the endless con-

veyer is to be stopped, wheel 22 is locked, permitting the clutch members 33 and 34 to slip with relation to each other.

The hub 35 also has a gear 48 fixed thereon which meshes with a gear 49 journaled on a shaft 50. The shaft 50 has a clutch member 51 fixed thereon, and the clutch member 51 cooperates with a clutch member 52 carried on the hub of gear 49. The clutch 51-52 may be of any desirable construction, but I find one having a positive lock, such as a pin 53 mounted in the clutch member 52 adapted to pass into an opening 54 of the clutch member 51, forms a desirable construction. The pin 53 has a lug 55 extending radially from the shaft 50 which is adapted to be engaged by a wedge 56 for withdrawing the pin 53 from opening 54 to render the clutch 51-52 inoperative. In the present instance, member 56 is pivoted on a pin 57 and provided with a spring 58 for normally holding it against the hub of clutch member 51 in the path of projection 55. The pin 53 is urged toward the clutch member 51 by a spring 59 pressing against its inner end so that the pin 53 will ride against the adjacent surface of clutch member 51 until it comes to the opening 54 when it will automatically pass into the latter. Also, when the shaft 50 has rotated to near the end of its revolution, wedge 56 engages the projection 55 to withdraw the pin 53 from the opening 54.

The shaft 50 also carries a cam 60 which is adapted to engage the roller 61 of a lever 62. The lever 62 is connected by means of a chain or other arrangement 63 to the wedge 56. The upper end of lever 62 is pivotally connected to a pin 64 which passes through the frame 5 and has one end adapted to engage openings 65 in plate 27. A spring 66 normally presses the pin 64 toward the plate 27.

The gears 48 and 49, together with the clutch members 52 and 34 will be continuously rotated during the operation of the device. With the parts in the positions indicated in Fig. 3 clutch 51-52 is in operative condition so that shaft 50 will be rotated until cam 60 moves the lever 62 which will permit the wedge 53 to rest against the hub of clutch 51 in the path of projection 55, and when the shaft 50 has rotated to near the end of its revolution the wedge withdraws the pin 53 from opening 54 to disconnect clutch member 51 from member 52. This movement of lever 62 also withdraws the pin 64 from opening 65 which permits the wheel 22 to rotate due to the continuous frictional engagement between clutch members 33 and 34. The wheel 22 and the conveyer will rotate until the pin 64 comes into engagement with the next opening 65 in ring 27. The spring 66 will automatically move pin 64 into said next opening 65 and

lock the conveyer against further movement, causing slippage between clutch members 33 and 34. This movement of pin 64 into said opening 65 moves lever 62 to raise the wedge 56 out of engagement with projection 55, permitting spring 59 to move pin 53 into engagement with clutch member 51, and as soon as said pin 53 comes into registration with opening 54 clutch members 51 and 52 will be locked together again for rotation until cam 60 again operates lever 62 when the cycle of movements will be repeated.

On the front end of shaft 50 is a cam 70 which is engaged by a roller 71. The roller 71 is mounted in the adjacent ends of links 72 and 73 which are at substantially right angles to each other. The link 73 is pivoted as at 74 to a member 75 fixed on the outer end of projection 24. The upper end of link 72 is pivoted as at 76 to a vertically sliding member 77. The part 24 has an upwardly extending guide 78 in which the member 77 is mounted. The arrangement is such that when the conveyer is locked against movement the upper end of member 77 will be in registration with one of the rods 19 so that when shaft 50 is operated cam 70 will move the member 77 up against said rod 19 to move the pie-tin holder 20 up in operating relation with a pie-engaging member 79. The member 79 is adapted to engage the inner side of a pie-crust A to hold the latter in a tin in the holder 20 while the rim is formed on said pie-crust. The member 79 is held against rotation by being fixed on the lower end of a member 80 mounted on a plate 81. The member 80 is preferably cylindrical, or at least has a portion cylindrical, upon which is mounted a gear 82. The gear 82 carries a bar 83 at its lower end and in the ends of the bar 83 are mounted two or more pie-pinching rollers 84. Each of the rollers 84 preferably carries a gear 85 fixed thereon which meshes with a gear 86 on the member 80. Thus, the gear 86 is held stationary and the gears 85 rotated around the gear 86, and this movement of the gears 85 around gear 86 causes rotation of the pie-pinchers 84 as the latter are moved around the edge of the pie by gear 82. Said gear 82 meshes with a gear 87 on a shaft 88. Said shaft 88 carries a clutch member 89 which engages a plane side of gear 90. A spring 91 holds the member 89 against the face of gear 90 so as to cause rotation of the pie-pinchers, as above described. The gear 90 meshes with a gear 92, and the latter is driven through shaft 93 and gears 94 from gear 39.

It sometimes occurs that the pie dough tends to stick to the member 79, and I preferably provide a stripper 95 in the under face of member 79 which is operated by a rod 96 which extends through member 80. A lever 97 engages the upper end of rod 96

and said lever is operated by a link 98 through a lever 99 which engages a cam member 100 on the front side of disc 70. With this arrangement, just after the cam 5 70 permits the pie-tin holder 20 to be lowered, stripper 95 is caused to press down on the pie A in the tin in member 20 to make sure that the pie dough is freed from the member 79.

10 In Fig. 1 I have indicated more or less diagrammatically a pie dough rolling device 101. This device may be any of the well-known devices for rolling out dough for pies, and is preferably operated from shaft 41, as indicated. The member 101 preferably discharges its dough when rolled out onto an adjacent tin in a holder 20. Said tin, of course, being placed into the member 20 by hand or otherwise. After 15 the rim and pinching has been done on the dough the pie is taken from holder 20 from the end of the machine indicated in Fig. 1 by hand or otherwise.

10 In Fig. 1 I have indicated a plurality of 25 members 79 and pie-pinching devices 84, and their operating parts. It will be apparent that one of these devices may be used, or when it is desired to form pies having different markings, the members 84 30 may have different shapes in the different forms so that by turning the member 81 on its central shaft 102 to bring a new head having the desired configurations in the members 84, desired pinchings or a desired 35 rim may be formed on the pie. All that is necessary to change from one head to the other is to loosen the thumb screws 103 and swing the latter on pins 104 to free the member 81, then rotate the latter about its shaft 40 102 to its new position, and then adjust the locking members 103 to lock the device in its new position. A dowel pin 105 may be provided to facilitate bringing the head to its new position and holding it there.

45 I claim:—

1. A pie crimping machine comprising a frame; two shafts journaled in the frame; a pie conveyor actuated by one of said shafts; a gear journaled on each of said shafts 50 with said gears meshing together; a disc clutch member rigidly attached to one of said gears; a disc clutch member fixed on one of said shafts and frictionally engaging the disc on said gear; and a spring 55 around said shaft and pressing against said frame for holding the disc clutch members together, said clutch permitting stoppage of said conveyor and continued movement of said pie crimping mechanism.

60 2. A pie crimping machine comprising a frame; two parallel shafts mounted in the frame; a gear journaled on each of said shafts with said gears meshing together; a disc clutch member fixed on one of said gears; a disc clutch member fixed on one of 65

said shafts and engaging the first-mentioned clutch member; a spring tending to hold said clutch members tightly together; a clutch on the other shaft having a connection with the gear on the last-mentioned shaft; pie lifting mechanism secured to said shaft and means for operating the last-mentioned clutch for transmitting interrupted movement to said pie lifter.

3. A pie crimping machine comprising a 75 frame; a shaft journaled in the frame; a sprocket wheel mounted in the frame around said shaft; an endless conveyer on said sprocket wheel; a pie holder on said conveyer; a pie crimping head mounted on the 80 frame above the pie holder; a stripper connected with the pie crimping head; a cam on said shaft; and a lever engaging said cam and connected with said stripper.

4. A pie crimping machine comprising a 85 frame; a shaft journaled in said frame; a sprocket journaled on the frame around said shaft; an endless conveyer on said sprocket; a plurality of pie holders on said conveyer and adapted to be brought to a predetermined 90 position adjacent said sprocket; a cam on said shaft; an arm fixed on the frame; a head slidably mounted in the frame; two links having their adjacent ends pivoted together and their remote ends pivoted to 95 said head and arm; and a roller journaled at the pivotal points of said links and engaging said cam, the cam being formed so as to press said head against the pie holder to raise the latter for a predetermined time.

5. A pie crimping machine comprising a frame; a shaft journaled in the frame; a sprocket wheel mounted on said frame around said shaft; an endless conveyer on the sprocket wheel; a guide on the frame 100 within the rim of said sprocket wheel; a head having a portion slidably mounted in said guide; a link pivoted to said head; a roller on said cam and journaled in the other end of said link; means for holding 105 the roller in a predetermined position relative to the shaft and cam; a pie holder on the conveyer with a portion adjacent said head; a crimping head mounted on the frame above said sprocket wheel; and a stripper 110 mounted on the crimping head and lever having a curved portion riding on said cam and connected with said stripper.

6. A crimping machine comprising a 115 frame; a head pivotally mounted on said frame; means for locking said head in different positions about its pivotal connection; a plurality of spaced pie crimping members mounted on said head; a pie holder mounted adjacent said head; and means for holding 120 said pie holder adjacent one of the crimping heads.

7. A pie crimping machine comprising a 125 frame; a head mounted on said frame with provision for rotating said head about a 130

pivotal point; a plurality of pie crimping position to be engaged by one of the strippers members mounted on said head; a pie holder when sits corresponding crimping member mounted beneath said head; means for locking the head in position for bringing any pie holder. In testimony whereof I have signed my name to this specification on this 12th day of December, A.D. 1921.

WILLIAM EHRLICH.
